TABLE

Hans F. Schult, Sr., Waverly, Iowa

Application March 18, 1954, Serial No. 417,101

2 Claims. (Cl. 45—131)

This invention relates to furniture, and more particularly to a table having a changeable top with which is associated improved means for providing ornamentation which is of such construction that a series of ornamental strips may be selectively disposed in position to be viewed through a transparent top panel.

One object of the invention is to provide the table with a hollow body having a transparent top panel and a bottom panel which is removably secured and carries upstanding brackets between which rollers are mounted, the rollers being engaged by portions of an endless web consisting of contrasting strips secured in end-to-end engagement with each other and extending between and trained about the rollers so that when the rollers are turned the web may be moved longitudinally and a selected one of the strips moved into position to be seen through the transparent top panel.

Another object of the invention is to provide a table having the web engaging rollers rotatably supported by brackets extending upwardly from the removable bottom panel so that when the bottom panel is removed, the brackets and the web engaging rollers will be moved downwardly out of the hollow body of the table and thus allow repairs to be made or another web applied to the rollers in place of a web already in use.

Another object of the invention is to provide a table of this character wherein one of the rollers is so constructed that it has frictional binding engagement with a portion of the web trained about it and thus allow the web to be readily moved longitudinally when the driving roller is turned.

Another object of the invention is to provide improved means for supporting the transparent top panel, this transparent panel resting upon flanged strips secured to walls of the body and not only supporting the transparent panel but also serving as supporting means for an ornamental trim which extends entirely about the body and constitutes a border which overlies and conceals the rollers and marginal edges of the upper flight of the ornamental web.

Another object of the invention is to provide a table of this character which is simple in construction and very easily operated.

The invention is illustrated in the accompanying drawings, wherein:

Fig. 1 is a perspective view of the improved table, a portion of the transparent upper panel being removed in order to clearly show the upper flight of the ornamental web;

Fig. 2 is a sectional view taken longitudinally through the table;

Fig. 3 is a transverse sectional view taken along the line 3—3 of Fig. 2;

Fig. 4 is a sectional view taken along the line 4—4 of Fig. 2;

Fig. 5 is a perspective view of the drive roller; and

Fig. 6 is a fragmentary view showing two strips or

2

sections of the ornamental web secured in end-to-end engagement with each other.

This improved table has a hollow body 1 which may be of any length and width desired and may be either 5 oblong, as shown, square or of any other outline desired. The hollow body has oppositely disposed side walls 2 and 3 and end walls 4 and 5 which are also in opposed relation to each other.

Supporting legs 6 are provided at corners of the table 10 and ends of the side walls and end walls are firmly secured to the legs in any desired manner. While upper ends of these legs have been shown protruding above upper edges of the walls, it will be understood that they may be flush with the walls or have ornamented upper 15 ends, if so desired.

Metal strips 7 are secured against inner surfaces of the walls by fasteners 8 which may be screws, small nails or the like, and these strips are formed with inwardly projecting flanges 9 which are spaced downwardly from 20 the upper edges of the walls such a distance that when a transparent top panel 10 is set at rest upon the supporting strips, its upper surface will be flush with the upper edge faces of the walls. The flanged strips also serve to support an ornamental trim 11 which extends entirely 25 about marginal portions of the transparent top panel and not only adds to the appearance of the table but also serves to conceal marginal portions of ornamental means mounted in the body and displayed through the transparent top panel 10.

The bottom of the body is closed by a bottom panel 12 which is secured along lower edge faces of the walls by a suitable number of screws 13 in order that the bottom panel will be firmly secured but may be removed when so desired. This bottom panel carries brackets 14 35 which are secured upon the bottom panel by bolts 15 and extend upwardly from the bottom panel at opposite ends of the side walls in close proximity thereto, as shown in Figs. 3 and 4, with their upper ends overlapping the supporting strips 7. The brackets rotatably support a number of rollers 16 which are in vertically spaced relation to each other, as shown in Fig. 3, and one of these rollers, which is indicated by the numeral 17, constitutes a drive roller and is rotatably mounted between lower portions of the brackets at one end of the table. This 40 drive roller has a centrally located shaft 18 which is of greater length than the shafts of the remaining rollers and projects from the drive roller such a distance that it passes through a slot 19 leading from the lower edge of one of the side walls, a knob 20 being rigidly mounted 45 upon the protruding end portion of the shaft 18 so that by grasping this knob the drive roller may be turned. Since the shaft 18 passes outwardly through a slot or notch leading from the lower edge of the side wall 3, it may be moved downwardly out of this notch and, 50 therefore, not interfere with ready removal of the brackets and the rollers from within the hollow table body when the screws 13 are removed and the bottom panel shifted downwardly. The rollers may be formed of wood or other suitable material and about the drive roller 17 is 55 provided a covering 21 formed of fabric or other suitable material which will have frictional binding engagement with a fabric web trained about the drive roller.

Referring to Fig. 2 it will be seen that the web 22, which may be formed of fabric or other suitable flexible material, extends longitudinally of the table and is trained about the various rollers, thus providing an endless web having upper and lower flights and a number of intermediate flights, according to the number of rollers supported by the brackets. This web consists of a plurality 65 of strips or sections 23 of such width that marginal portions of the upper flight will be overlapped by the ornamental trim 11. Therefore, margins of the upper flight

will be completely concealed by portions of the trim extending along the side walls and since the upper ones of the rollers are overlapped by the trim extending along the end walls, the brackets and any space between walls of the table and the rollers and marginal portions of the web will be entirely concealed and not detract from the appearance of the table. Portions of the web trained about the various rollers have close fitting engagement therewith and since the drive roller is provided with a covering 21 of fabric or other suitable material having frictional binding engagement with the web, the drive roller, when turned, will very effectively impart movement to the web and the upper flight will be moved longitudinally to adjusted positions. This web consists of a suitable number of sections 23 which are of contrasting colors or designs and secured together at their ends by the seams 24 shown in Fig. 6 and each section is of such length that when it is in position to constitute the upper flight of the web, both ends will be concealed from view of a person looking at the transparent top panel. In Fig. 6 one section or strip forming the web has been shown as red and the other as green, but it will be understood that they may be of any colors desired and also ornamented in such a manner that they will be of a distinctive contrast to each other. Therefore, by turning the drive roller, a section constituting the upper flight of the web may be shifted longitudinally out of its position in which it is displayed through the transparent top panel, and another strip or section moved into place where it may be seen. This will materially change the appearance of the table and add to its attractiveness.

While it has been stated that the rollers are mounted at ends of the table adjacent the end walls 4 and 5, it will be understood that they could be so disposed that the rollers extend longitudinally of the side walls instead of being parallel to the end walls, in which case the flights of the web will extend transversely of the table instead of longitudinally thereof. Various other arrangements of the rollers may be made for controlling directional movement of the web in accordance with whether the table is oblong, square, or any other shape desired.

When the strips of fabric or other material from which the web is formed become soiled or an entirely different pattern desired, it is merely necessary to remove the screws 13 and shift the bottom panel downwardly away from the open bottom of the body of the table. The brackets, together with the rollers and the web, will be removed from the table body, along with the bottom panel, and by removing the bolts securing the brackets at one side of the bottom panel, these brackets may be shifted out of engagement with the shafts or pintles of the rollers and the entire web removed and replaced by another.

As this invention may be embodied in several forms without departing from the spirit or essential characteristics thereof, the present embodiment is therefore illustrative and not restrictive, since the scope of the invention is defined by the appended claims rather than by the description preceding them; and all changes that fall within the metes and bounds of the claims or that form their functional as well as conjointly cooperative equivalents, are therefore intended to be embraced by those claims.

What I claim is:

1. A table of the character described comprising a rectangular frame embodying spaced parallel side walls and transverse end walls, said side walls having a substantial height, supporting legs attached to the frame at the corners thereof, a transparent top wall panel fitted in the frame at the top edges of said walls, a bottom wall covering the underside of the frame and extending across the bottom edge surfaces of the side and end walls, fasteners remov-

ably securing the bottom wall to said bottom edge surfaces, an upright L-shaped bracket upon the top side of the bottom wall at each side edge and adjacent to each end of the bottom wall, each bracket including a vertical relatively wide leg spanning the space between said bottom wall and the top wall panel and a horizontal leg extending inwardly on the bottom wall and secured thereto, the wide vertical legs of the brackets on one side of the bottom wall each facing the corresponding leg of a bracket on the opposite side to form a pair of spaced supports, a set of vertically spaced rollers extending across the space between and rotatably mounted on each pair of spaced supports, the lowermost roller of one set constituting a driving roller and being of greater diameter than the overlying rollers, a friction material covering said driving roller, an operating shaft extending axially from one end of said driving roller to the outer side of the adjacent side wall through a slot in the latter wall which opens through the bottom edge thereof, and an endless web extending back and forth between the sets of rollers and trained around the rollers and consisting of a number of different joined sections designed to be successively moved into position beneath and for display through the transparent top wall panel.

2. A table of the character described comprising a rectangular frame embodying spaced parallel side walls and transverse end walls, supporting legs attached to the frame, angle strips disposed along the inner sides of the side and end walls and each having a horizontal part spaced below the top of the adjacent frame wall and a depending part secured to the adjacent frame wall, a transparent top wall panel fitted in the frame and supported on the horizontal parts of the angle strips, the bottom wall covering the underside of the frame and secured to the side and end walls at the bottoms thereof, means removably securing the bottom wall to said side and end walls, an upright L-shaped bracket upon the top side of the bottom wall at each side edge and adjacent to each end of the bottom wall, each bracket including an upright relatively wide leg spanning the major extent of the space between said bottom wall and the top wall panel and a horizontal leg extending inwardly on the bottom wall and secured thereto, the top ends of the vertical legs of said brackets overlapping and being positioned against the depending part of an angle strip and maintained by the said depending part of the angle strip in spaced relation with the adjacent side wall, a set of vertically spaced rollers extending across the space between and rotatably mounted on each pair of spaced supports, the lowermost roller of one set constituting a driving roller, an operating shaft extending axially from one end of said driving roller to the outer side of the adjacent side wall through an opening in the latter wall, and an endless web extending back and forth between the sets of rollers and trained around the rollers and consisting of a number of different joined sections designed to be successively moved into position beneath and for display through the transparent top wall panel.
